HIGH-FREQUENCY OSCILLATOR OF THE
SECONDARY ELECTRON-EMISSION TYPEClarence W. Hansell, Port Jefferson, N. Y., as-
signor to Radio Corporation of America, a cor-
poration of Delaware

Application May 4, 1944, Serial No. 534,066

21 Claims. (Cl. 250—36)

1

The present invention relates to improvements in electron multiplier tubes and circuits therefor, and particularly to such tubes having a pair of secondary emissive cathodes between which electrons flow back and forth to produce electron multiplication.

An object of the invention is to provide an improved mechanically rugged electron tube structure whose individual elements have large surface areas as a result of which the effects of temperature are minimized.

Another object is to provide a vacuum tube structure having a pair of secondary emissive cathodes of large surface area spaced close to each other compared to the diameters of the cathodes, and having an anode of larger diameter than the cathodes surrounding the space between the cathodes.

Another object is to provide a highly efficient high power tube useful for induction heating purposes and capable of generating alternating current power ranging up to hundreds of kilowatts at frequencies from near zero to low radio frequencies up to the order of a megacycle, and particularly useful with high efficiency in the range extending from audio frequencies up to 100,000 cycles.

Another object is to provide a compact, rugged and relatively inexpensive high power tube for use in converting power at one frequency including direct current to power at another frequency.

Another object is to provide a system for obtaining output power at a frequency lower than the excitation power and with reduced losses and smaller dimensioned tubes than would be required if the output power were of the same or a multiple of the input frequency.

Another object is to provide an electron emission switch in which the emission is turned on and off by turning on and off a radio frequency excitation current.

A further object is to provide an electron emission switch having a pair of secondary emissive cathodes in which the emission is turned off and on by applying excitation continuously in the form of radio frequency current and by applying and removing a bias between the cathodes.

A still further object is to provide a vacuum tube having secondary emissive cathode surfaces which are cooler than any other surface exposed to the vacuum, as a result of which deactivation of the secondary emissive cathode surface is prevented.

In the preferred construction of the tube of the invention, the tube is of the evacuated type and

2

employs a pair of secondary emissive cathodes whose diameters are large compared to the spacing therebetween. The cathodes may be circular discs or plates, rectangular or of any suitable configuration, and their active surfaces are cooled so that they are the coolest surfaces exposed to the vacuum. An anode surrounds the cathodes and is made thicker in the region between cathode surfaces than at other places as an aid to conducting away the heat produced on the active anode surfaces.

The close spacing between cathodes as compared with their diameter makes the production of electron emission substantially independent of the instantaneous anode-to-cathode voltage. If the spacing between cathodes is large, the anode-to-cathode voltage will affect the electron paths and the electron transit time between cathodes, in which case it would be necessary to start A. C. operation with a low anode-to-cathode voltage and then increase the voltage. By using a small ratio of spacing between cathodes to cathode diameter, in accordance with the preferred construction of the tube of the invention, it is possible to start emission while the anode to cathode potential is high, without dropping temporarily. By making the secondary emissive cathodes the coolest surfaces exposed to the vacuum, deactivation is prevented, and continued reactivation is continuously assured. Such deactivation might otherwise occur due to the loss from the cathodes of activating material which tends to migrate to cooler surfaces by the process of sublimation. The thicker portions of the anode at the places closest to the cathodes insure better heat dissipation from the anode surface receiving the electrons, and also minimize the number of electrons which might tend to strike the glass seal. By curving certain portions of the anode or by placing target portions between the anode and glass envelope, it is further possible to prevent any electrons from striking the glass. Of course, the anode itself might form part or nearly all of the evacuated envelope of the tube.

In practice I have found that it is possible by suitable A. C. excitation to cause a growth of electron emission from suitably activated secondary emission cathodes which are completely cold. Apparently there are enough electrons emitted from surfaces due to light, cosmic rays, evaporation and condensation processes or other causes so that, except for a little initial hesitation, growth of emission can be accomplished. Once growth has taken place it appears that a very small emission persists for some time after

secondary emission excitation is removed so that starting after brief periods of removal of excitation, is prompt and reliable.

A more detailed description of the invention follows in conjunction with drawings, wherein;

Fig. 1 illustrates the invention in a high power converter for converting direct or low frequency alternating current to higher frequency current;

Fig. 1a illustrates the same system as Fig. 1, with tuned circuits in the form of sections of transmission line;

Fig. 2 is a modification of Fig. 1 and illustrates another way of keying the tube than by modulating the radio frequency current; and

Fig. 3 illustrates the tube of the invention used as a switch or circuit breaker.

Referring to Fig. 1 in more detail, there is shown my improved evacuated electron discharge device 13 employed as a high power tube in a circuit for converting direct current or low alternating frequency current supplied from a power source 11 to a higher frequency current utilized for heating induction heating apparatus 12.

The vacuum tube 13 comprises a pair of secondary emissive cathodes 1 in the form of plates or discs whose confronting surfaces are constituted of, or coated with suitable material to give the best secondary emission possible. Cathodes 1 are preferably spaced apart only a short distance compared to the diameters of the cathodes, as shown. This small spacing is not absolutely essential to obtaining a workable converter but it provides great convenience in operation by making it possible to start and stop operation of the converter without momentarily changing the power supply potential. If the cathodes were designed with a large ratio of spacing to diameter the electric field between anode and cathodes could inhibit the growth of secondary emission.

Surrounding the cathodes is a cylindrical metallic anode 2 having a relatively thick portion in the region adjacent the space between the cathodes. This thick portion, shown as a bump, insures better heat dissipation from the bombarded anode surface and also minimizes the tendency for electrons to flow toward the anode portion adjacent the seal to the glass envelope 3. The anode is slightly curved at its extremities 4 to prevent electrons from striking the glass. It will thus be seen that the anode itself forms a large part of the evacuated envelope.

The cathodes are maintained the coolest surfaces of the tube elements in order to prevent deactivation; that is, loss of activating material which might otherwise flow to cooler surfaces by the process of sublimation. This is achieved by means of a flow of cooling fluid, such as water or air, passing in through inlets 5 and out through outlets 6. The inlets and outlets are in the form of metallic coaxial conduits, as shown.

In practice the activating material may be one or a combination of elements of the most easily ionizable kind condensed or bound on an oxidized or otherwise chemically complex surface.

There are a number of types of composite surfaces for producing a large ratio of secondary emission electron current due to an impinging electron current. Those having the highest ratio appear to have the common limitation that they are spoiled, at least temporarily, by overheating. I believe that this loss of activation is primarily, though not entirely due to evaporation of activating material from the surface. By reversing the process to cause condensation on

the surface, the cooled cathodes can be protected from deactivating and may be continuously activated instead. By this means, good use may be made of such activating materials as caesium, rubidium, potassium, sodium, barium, radium, lithium, lanthanum and strontium, but particularly caesium. It is believed that caesium is the best known activating material but also it is the most volatile and quickly evaporated from a surface when the surface is allowed to operate at a higher temperature than other surfaces exposed to the vacuum. By keeping the active areas of the cathode at a lower temperature than any other areas exposed to the vacuum even volatile caesium can be kept on the cathode surfaces.

The cathodes are coupled to opposite terminals of a parallel tuned circuit 7 which supplies radio frequency excitation potentials to the cathodes. Tuned circuit 7 is coupled to tuned circuit 8 forming the output of a source of high radio frequency power 9. Source 9 may for example, be an oscillator or a power amplifier supplying 100 megacycle energy to tuned circuit 8. Source 9 is modulated or keyed by an oscillator-modulator 13, which for example modulates or pulses the output of source 9 at a repetition rate of 50,000 cycles per second.

The output of tube 13 is coupled to a circuit 14 which is tuned to the 50,000 cycle modulating frequency and which supplies heating energy to induction heating apparatus 12. Apparatus 12 is shown as a crucible or pot, although it may be any desired type of equipment.

A power source 11 supplies high voltage, let us say by way of example only, 15,000 volts direct current or low frequency alternating current sixty cycles by way of illustration to opposite terminals of a condenser 15 which terminals are connected to the tuned circuits 7 and 14 as shown.

In the operation of the system of Fig. 1, tuned circuit 8 supplies pulses of high frequency energy to tuned circuit 7. These pulses are repeated at a 50 kilocycle rate while the high frequency energy is at 100 megacycles. Both circuits 7 and 8 are tuned to the 100 megacycle frequency and, in practice, would consist of sections of transmission line, such as concentric lines rather than the equivalent lumped circuits. This is shown in Fig. 1a. This energy excites the secondary emissive cathodes 1 setting up a 100 megacycle A. C. electric field between them. The spacing between the cathode surface is correlated to the excitation radio frequency and the voltage between the cathodes. Obviously, this voltage affects the transit time of the electrons traveling between the cathodes. This transit time should be of the order of one-half of the excitation frequency cycle. Electrons will leave either cathode and travel to the other cathode under the influence of the applied radio frequency field, and only those electrons near the outside edges of the cathodes escape to the anode 2. An electron leaving the center of the surface of one cathode will be drawn by the radio frequency field to the other cathode where it will cause the emission of several secondary electrons. These secondary electrons will, in turn, cross the space between the cathodes and each produce several additional secondary electrons. This process will be repeated until there are an enormous number of electrons flowing back and forth between the cathodes. At the beginning of this electron building up process, an electron released at the

center of one cathode surface will produce an increase in electrons only at or near the center, but as soon as the electrons become numerous a space charge will be built up between the cathodes which will force the phenomena to spread out radially from the center until the whole adjacent surfaces of the cathodes are active in producing emission. When the electrons reach the edges of the cathodes, there will be a continual loss of electrons to the anode and a current will flow from the anode to the cathodes. This current, depending upon the diameter of the cathodes, may easily be as high as 30 amperes and higher. The current carrying capacity of the tube is determined primarily by the circumference of the cathodes. The shape of the cathodes and the anode may be scalloped or made to be irregular to increase this circumference where the greatest possible ratio of anode current to tube dimensions is desired. In general I prefer simpler configurations because they are easier and cheaper to provide.

It should be understood that, for proper emission, the instantaneous anode potential at times when anode current flow is desired, should not be too high and must be properly correlated to the spacing between the cathodes and the cathode diameter so that electrons are not drawn directly to the anode and thus the desired building up of the electrons in the space between the cathodes prevented. In practice, however, such a feature may be relied upon for making and breaking (i. e., interrupting) the emission at the frequency of the output circuit. For example, in a carefully designed tube, the pulling out of the electrons from between the cathodes due to the anode-to-cathode potential, may be so great as to inhibit growth of a substantial electron emission except in time periods when the oscillations in the output circuit have reduced the anode-to-cathode potential to a low value. This will then provide the necessary conditions for self oscillation at the output frequency. With such a self oscillating tube, source 9 may generate continuously and source 13 may be eliminated. For this self oscillating combination, it should be noted, oscillations can start only while the potential of the anode-to-cathode power source is low, but after they have started, the potential may be increased, not too rapidly, to the operating value.

Circuit 14 is tuned to the modulating or keying frequency, in this case 50,000 cycles per second. Output from circuit 14 is at peak voltage about equal to, or somewhat less than the 15,000 volts of power source 11. If power at a lower potential is desired a transformer circuit may be interposed between circuit 14 and the load 12.

Fig. 2 is a modification of the circuit of Fig. 1, and illustrates another way to key or modulate the tube 10. The same parts in Figs. 1 and 2 are given the same reference numerals, while the equivalent parts have the same reference numerals with a prime designation. In Fig. 1, the megacycle radio frequency current is supplied to tube 10 in pulses, while in Fig. 2, the 100 megacycle current is supplied continuously to the tube 10 and reliance is placed on superimposing a lower frequency excitation (the output frequency) between the cathodes upon the 100 megacycle excitation to assist in keying the tube. This superimposing is obtained by a feed back circuit composed of coils 16 which are coupled to the output circuit 14' and connected back to the input circuit 7'. The direct current bias from source

17 prevents current from flowing between anode and cathodes by preventing the growth of secondary emission. This direct current bias is balanced out to zero or to a low value once per cycle by the feed back excitation at the time it is desired that anode current should flow. This feed back excitation is the coupling between output circuit 14' and input circuit 7'. When there is zero bias on the cathodes, the direct current from power source 11 flows through tube 10 between anode and cathodes. The direct current flowing in pulses develops the output voltage which is available in the load circuit 18. This load circuit may be any desired type of circuit, such, for example, as induction heating apparatus.

For starting the arrangement of Fig. 2, the bias from source 17 may be reduced momentarily or, preferably, the bias from 17 is obtained by rectifying a little of the power from circuit 14' to provide a direct current potential which adjusts itself automatically to cause starting and correct conditions during operation. If bias source 17 is driven from the main power supply it is preferably connected with the same source as 11 so that their potentials vary together.

Fig. 3 illustrates the use of the improved tube of the invention as a switch or circuit breaker, capable of handling several hundreds or even one thousand amperes at extremely high D. C. potentials such as might be employed in the long distance transmission of electrical power. Much effort has been put into the development of D. C. transmission because of the economies in line construction which it offers, once the needed auxiliary equipment is available. A source of high voltage anywhere in the range between 20,000 volts and 300,000 volts is represented by box 20. This source may be a power house having conventional alternating current generators and rectifiers, and may be located at a remote point relative to the loads. A transmission line TL connects this power house to the converter apparatus 21 through the tube 10. The secondary emissive cathodes of tube 10 are excited from tuned input circuit 7, in turn coupled to high frequency source 9. A pair of leads 22 couple the oscillator source 9 to a power supply which provides the anode voltage for the oscillator 9 or the alternating current power to the rectifier in the oscillator apparatus 9. Power switches 23a and 23b are provided in series with the leads 22. An overload relay 25 controls switch 23a. Switch 23b is manually operated. The direct current-to-alternating current converter 21 may be any suitable apparatus such as the "Ignitron" D. C. to A. C. power connector, or it may be the same type of converter shown in Figs. 1 and 2 utilizing my improved double secondary emissive cathode tube. The output of converter 21 is at low alternating current frequency, 60 cycles for example, and supplies various loads. A branch line T'L' couples TL to other systems similar to that shown to the right of T'L'.

In the operation of the system of Fig. 3, as soon as power switch 23b is closed, direct current from the power source 20 will flow over line TL and through tube 10 to the converter 21. In the case of an overload being drawn through converter 21, the voltage across resistance R will rise so that the winding of relay 25 (which is in parallel with resistance R) will draw enough current to open switch 23a and thus protect the equipment.

The trouble with conventional types of switches of the contact type is that they involve tremendous technical problems when designed to interrupt voltages as high as 200,000 volts. Such conventional switches are, in addition, extremely expensive and have extremely large dimensions. Further, the use of conventional switches requires the replacement of contacts after usage for a little while. The circuit breaker of the present invention of Fig. 3, however is compact, relatively indestructible and inexpensive.

The following are additional advantages provided by the improved tube of the invention: It is of simplified construction compared to the hot cathode tubes of similar rating; and the tube of the invention has much smaller dissipation of power in the form of heat at the cathodes. This last advantage is due to the fact that the improved tube produces emission only as it is needed, whereas the hot cathodes produce emission continuously, and continuously require power for this purpose.

The electron discharge device of the invention, when built with dimensions which are commonly used for transmitting vacuum tubes, can be used to key the output of a rectifier and the input to a radio frequency amplifier at 20,000 volts and a power of 600 kilowatts. Simply turning on and off the 300 to 500 watts of radio frequency cathode input can switch on and off the 600 kw. direct current power in the manner shown generally in Fig. 3 or alternatively, the same thing may be accomplished by applying or removing a direct current bias between the cathodes. Thus, a tube of the invention may act as a series relay, and when designed in suitable sizes can convert direct current power of thousands of kilowatts into alternating current power at relatively high efficiency. For example, a unit about the size of a railway mercury arc rectifier tank might very well turn on and off several hundred and even 1000 amperes at 300,000 volts with a radio frequency control energy of only about 10 to 50 kilowatts depending upon the secondary emission ratio of the cathode surfaces and the degree of vacuum maintained in the tube, largely due to low cathode temperature condensing volatile materials.

It should be understood that the values mentioned in this specification for the voltages and frequencies are only illustrative and not limitative, and that different values may be used and properly correlated.

I claim:

1. An electron discharge device suitable for producing a high power output, comprising a pair of spaced cathodes having secondary emissive surfaces facing each other, an anode surrounding the space between said cathodes, a source of high frequency current coupled between said cathodes for exciting them, means for interrupting the emission from said cathode surfaces at a frequency lower than the excitation frequency, and an output circuit coupled to said anode for deriving power at said lower frequency.

2. An electron discharge device suitable for producing an alternating current power output, comprising a pair of parallel spaced secondary emissive cathode surfaces facing each other, an anode surrounding the space between said cathodes, a source of radio frequency current coupled between said cathodes for exciting them, a modulator coupled to said source for modulating the source at a frequency substantially less than said radio excitation frequency, and an output circuit

tuned to the modulation frequency coupled to said anode.

3. An electron discharge device suitable for producing a high power output, comprising a pair of parallel spaced secondary emissive cathode surfaces facing each other, an anode surrounding the space between said cathodes, a source of radio frequency current coupled between said cathodes for exciting them, a modulator coupled to said source for modulating the source at a frequency in the range of audio frequencies up to 1,000,000 cycles, and an output circuit tuned to the modulation frequency coupled to said anode.

4. A power system suitable for induction heating, comprising an evacuated electron discharge device having a pair of parallel spaced secondary emissive cathode surfaces facing each other, an anode surrounding the space between said cathodes, a source of radio frequency current coupled between said cathodes through an input circuit tuned to the frequency of said source, means for keying said source at a frequency substantially less than said radio frequency, as a result of which pulses of radio frequency energy are supplied to said cathodes, said pulses being repeated at the keying frequency, an output circuit tuned to said keying frequency and coupled to said anode, and a power source of direct current or low alternating current having opposite terminals coupled between said input and output tuned circuits.

5. An evacuated electron discharge device suitable for producing high power output, comprising a pair of parallel spaced cathodes having secondary emissive surfaces facing each other, an anode surrounding the space between said cathodes, a tuned input circuit in the form of a section of transmission line coupled between said cathodes, a source of high frequency current coupled to said section of line, said line being tuned to the frequency of said source, means for modulating the output of said tube at a frequency substantially different from the frequency of said source, and an output circuit tuned to said modulating frequency coupled to said anode for deriving output from said device.

6. An evacuated electron discharge device suitable for producing high power output, comprising a pair of parallel spaced cathodes having secondary emissive surfaces facing each other, an anode surrounding the space between said cathodes, a tuned input circuit coupled between said cathodes, a source of radio frequency current coupled to said tuned input circuit, said input circuit being tuned to the frequency of said source, means for interrupting the emission from said cathode surfaces at a frequency substantially lower than said radio frequency, and an output circuit coupled to said anode and tuned to said lower frequency, said interrupting means including a bias source for said cathodes and a feed back circuit between said input and output tuned circuits.

7. An electron discharge device devoid of a directly heated cathode, comprising a pair of electron impermeable parallel spaced cathode plates having secondary emissive surfaces facing each other, the distance between said cathodes being short compared to the diameters of said secondary emissive surfaces, and a single electron collecting anode surrounding the entire space between said cathodes.

8. An electron discharge device comprising a pair of parallel spaced cathode plates having secondary emissive surfaces facing each other, the

distance between said cathodes being short compared to the diameters of said secondary emissive surfaces, an anode surrounding the space between said cathodes, a source of high frequency current coupled between said cathodes for exciting them, means for interrupting the emission from said cathode surfaces at a frequency lower than the excitation frequency, and an output circuit coupled to said anode for deriving power at said lower frequency, said output circuit being tuned to said lower frequency.

9. An electron discharge device comprising a pair of spaced cathodes having secondary emissive surfaces facing each other and located in an evacuated envelope, an anode surrounding the space between said cathodes, means supplying cooling fluid to said cathodes at such temperatures as to make said secondary emissive surfaces the coolest parts of said device exposed to said vacuum, a source of high frequency current coupled between said cathodes for exciting the same, means for interrupting the emission from said cathode surfaces at a frequency lower than the excitation frequency, and an output circuit coupled to said anode for deriving power at said lower frequency.

10. An electron discharge device including a disc-like cathode having a surface coated with secondary emissive activating material, an anode surrounding said cathode and enclosing an evacuated space, and means for preventing loss of activating material from said cathode to other parts of said device comprising cooling fluid inlet and outlet tubes maintaining said surface the coolest surface exposed to the vacuum, whereby deactivation of said secondary emissive cathode is prevented, said inlet and outlet tubes having their longitudinal axes substantially perpendicular to the plane of said cathode.

11. An electron discharge device including a pair of parallel spaced cathode plates having their confronting surfaces coated with secondary emissive activating material, said secondary emissive cathodes being located within an evacuated container a pair of inlet tubes entering said container at right angles to said plates and supplying cooling fluid to said cathodes, and a pair of outlet tubes entering said container at right angles to said plates for removing the cooling fluid after it has cooled said cathodes, whereby said cathodes are maintained the coolest surfaces exposed to the vacuum.

12. An electron discharge device including a pair of parallel spaced cathode plates having their confronting surfaces coated with secondary emissive activating material, said secondary emissive cathodes being located within an evacuated container, an inlet tube and a coaxial outlet tube for supplying cooling fluid to each cathode, said tubes entering said container and being sealed thereto, the coaxial tubes for said cathodes entering said container from opposite sides thereof.

13. A high power converter system of direct current or low alternating current to energy in the frequency range from audio to 1,000,000 cycles, comprising a vacuum tube having a pair of parallel spaced cathode plates whose confronting surfaces are coated with secondary emissive activating material, the spacing between said plates being shorter than the diameters of said plates, an anode surrounding the space between said cathode plates, means for maintaining said cathodes the coolest surfaces exposed to the vacuum, a tuned input circuit coupled between said cathodes, a source of radio frequency excitation cur-

rent coupled to said tuned input circuit, said input circuit being tuned to said radio frequency, means for modulating said tube at a frequency substantially lower than said radio frequency, an output circuit coupled to said anode and tuned to said modulating frequency, a power source of direct current or low frequency alternating current having opposite terminals connected from a direct current standpoint to said input and output tuned circuits, whereby said vacuum tube produces power output at a peak potential close to the potential of said power source and at said modulating frequency.

14. An electron discharge device devoid of a directly heated cathode, comprising a pair of electron impermeable parallel spaced cathode plates having coated secondary emissive surfaces facing each other, the distance between said cathodes being short compared to the diameters of said secondary emissive surfaces, an anode surrounding the entire space between said cathodes, said space being evacuated, that portion of the anode adjacent said space being thicker than the other portions of said anode.

15. An electron discharge device comprising a pair of parallel spaced cathode plates having coated secondary emissive surfaces facing each other, the distance between said cathodes being short compared to the diameters of said secondary emissive surfaces, an anode surrounding the space between said cathodes, said space being evacuated, a tuned circuit coupled between said cathodes, and a source of radio frequency current coupled to said tuned circuit, said tuned circuit being tuned to said radio frequency.

16. An electronic switch between a power source of high voltage and a load, comprising an electron discharge device having a pair of parallel spaced secondary emissive cathode surfaces facing each other, the distance between said cathodes being short compared to the diameter of said secondary emissive surfaces, an anode surrounding the space between said cathodes, said space being evacuated, a transmission line coupling said source of high voltage to said anode, a source of radio frequency control energy, a circuit tuned to said radio frequency coupled between said cathodes and also coupled to said radio frequency source, and a load coupled to said cathodes.

17. An electronic switch between a power source of high voltage and a load, comprising an electron discharge device having a pair of parallel spaced secondary emissive cathode surfaces facing each other, the distance between said cathodes being short compared to the diameter of said secondary emissive surfaces, an anode surrounding the space between said cathodes, said space being evacuated, a transmission line coupling said source of high voltage to said anode, a source of radio frequency control energy, a circuit tuned to said radio frequency coupled between said cathodes and also coupled to said radio frequency source, a converter of direct current-to-low frequency alternating current coupled between said cathodes and a load.

18. An oscillator comprising an evacuated electron discharge device having impermeable plate-like cathodes with secondary emissive coated surfaces facing each other, a source of very high frequency potential coupled between said cathodes and adjusted to obtain a growth of secondary emission from the cathodes, the distance between said cathodes being short compared to the diameter of said secondary emissive surfaces, an electron collecting anode surrounding the entire

space between the cathodes to provide an electric field which can inhibit substantial emission when the instantaneous anode-to-cathode potential is high but which permits growth of emission when the anode-to-cathode potential is low, thereby providing the conditions for self oscillation.

19. An electron discharge device suitable for producing a high power output, comprising a pair of spaced plate-like cathodes having secondary emissive surfaces facing each other, the distance between said cathodes being short compared to the distance across the secondary emissive surface area of each of said secondary emissive surfaces, an anode surrounding the space between said cathodes, a source of high frequency current coupled between said cathodes for exciting them, means for interrupting the emission from said cathode surfaces at a frequency lower than the excitation frequency, and an output circuit coupled to said anode for deriving power at said lower frequency.

20. An electron discharge device including a pair of parallel spaced cathode plates having their confronting surfaces coated with secondary emissive activating material, the distance between said plates being short compared to the distance across the secondary emissive surface area of each of said plates, said secondary emissive cathodes being located within an evacuated container, at least one inlet tube entering said container

and supplying cooling fluid to said cathodes, and at least one outlet tube entering said container for removing the cooling fluid after it has cooled said cathodes, whereby said cathodes are maintained the coolest surfaces exposed to the vacuum.

21. An electric tube having a cathode within and spaced from a surrounding envelope, said cathode having a coating of secondary emissive material thereon, and means for preventing loss of activating material from said coating comprising means for cooling said cathode to maintain it at a lower temperature than any other portion of the tube within said envelope.
